CAST WINDOW SHUTTER

Ralph N. Polen, St. Petersburg, Fla.

Application August 31, 1955, Serial No. 37,736

Term of patent 14 years

(Cl. D13—1)

Fig. 1

Fig. 2

Fig. 1 is a front elevation view of a cast window shutter showing my new design; and

Fig. 2 is a cross sectional view on line 2—2 of Fig. 1.
I claim:

The ornamental design for a cast window shutter, as shown.
